METHOD OF MAKING A TOOTH BRUSH

Torazo Nishio, Jamaica, N. Y.

Application March 18, 1936, Serial No. 69,444

2 Claims. (Cl. 300—21)

This invention relates to a tooth brush, and more particularly to a bamboo tooth brush of the type in which bunches of bristles are inserted in groups of holes in the bamboo and are anchored 5 therein by means of metal clips.

One object of the present invention is to provide an improved bamboo tooth brush having improved sheet metal clips for anchoring the bristles in such manner that the brushes may be 10 sterilized and the bristles are effectively and permanently retained in place.

Another object of my invention is to provide an improved bristle anchoring clip consisting of a sheet metal stamping having protruding portions 15 adapted to form shallow grooves in the sides of the bristle receiving hole, and a further object is to provide the clip with one or more portions of reduced dimensions to permit bending or twisting of the clip to resist withdrawal from the said 20 hole in the bamboo brush head.

Still another object of my invention is to provide an improved method of anchoring the bristles in the head.

With these and other objects in view, my invention consists in the novel construction and arrangement of parts and in the method hereinafter described with reference to the accompanying drawing, and particularly pointed out in the appended claims, it being understood that various 30 changes in the form and proportions of the parts may be made without departing from the spirit of the invention or sacrificing any of the advantages thereof.

In the drawing Fig. 1 is an enlarged side view of 35 a bamboo tooth brush with a portion thereof in sections; Fig. 2 is an enlarged view showing one of the holes in the head of the tooth brush; Fig. 3 is an enlarged section showing one form of my improved clip in position to grip the bristles in 40 the head of the brush; Figs. 4, 5 and 6 show three slightly modified forms of my improved clip, and Figs. 7 and 8 are views showing one form of the improved clip, Fig. 7 indicating the position of the clip while being introduced, and Fig. 8 showing 45 the final position.

Referring to the drawing, the head 10 of the bamboo tooth brush is integral with the stem or handle 11, being formed from a strip of bamboo with the hard natural outer skin of the bamboo 50 forming one face—preferably the back or outer face 12 of the brush. Suitable holes or recesses 13 are bored or formed in the head 10 and the bunches of bristles 14 are introduced into these holes 13 after being doubled over the retaining 55 clips 15, Fig. 1.

My improved clip is formed from rustless sheet metal and consists of a small stamping. In the form shown at Fig. 4 of the drawing, the clip 15 has a body part 16 with two similar side arms 17, the total width of the clip being slightly greater 5 than the diameter of the hole as indicated by the dot and dash lines 18 at this figure, so that when the clip is inserted in the hole with the bristles folded over the body 16 between the arms 17 the side extremities 19 of the clip form two shallow 10 diametrically opposite grooves 21, Fig. 2 in the comparatively soft wood of the bamboo brush head, and this clip is made with parts 20 at the base of the arms 17 of reduced dimension so that the arms 17 may bend and/or twist inwardly as 15 shown at Fig. 3 when the clip is pressed into the base of the hole, and the central part of the body 16 is also of reduced dimensions so that this part may also be bent in such manner that the protruding parts 19 of the clip are moved out of 20 alignment with the grooves 21 formed in the bamboo so that withdrawal of the clip is prevented.

Referring to Fig. 5 of the drawing the clip here shown is stamped from thin sheet metal preferably of a suitable rust-proof alloy and is shaped 25 to provide side portions 22 that extend into the walls of the hole 18, these parts 22 being tapered towards the leading edge of the clip as it is advanced into the hole with the bristles folded over the curved edge 23. The clip shown at Fig. 6 30 of the drawing is somewhat similar in construction, but the lower edge 24 of the clip shown at Fig. 5 is curved while the lower edge 25 of the clip shown at Fig. 6 is straight, and in both clips the mid-portion forms a waist 26, Fig. 5, and 27, Fig. 35 6, of reduced dimensions so that the clips may be bent or distorted when they are forced into the extremities of the holes so that the protruding side parts 22 are not in alignment with the 40 grooves 21 formed in the sides of the holes during the introduction of the clips, and withdrawal is thus prevented.

In the diagrammatic views Figs. 7 and 8, Fig. 7 shows the position of one of the improved clips (such as the clip shown at Fig. 5) as it is introduced into the hole 29, and Fig. 8 shows the position of the same clip after it has been forced into its final position and is bent, tilted, distorted or displaced in such manner that the grooves 21 formed in the sides of the hole by the introduction 50 of the clip are incapable of permitting the withdrawal of the clip and bristles.

The clip is so constructed as to embrace the bristles and consists of thin sheet metal adapted to be distorted as soon as the clip reaches its 55

final anchoring position, one or more portions of the clip being made of reduced dimensions to permit this distortion. During the introduction of the bristles by the usual setting implement, the 5 clip is in the form of a grooved or U-shaped perfectly flat member, having side edges that protrude beyond the diametrical dimension of the bore, which latter is thus grooved on both sides by such edges during the introduction of the 10 bristles, and when the clip reaches its anchoring position, the setting implement distorts or displaces the thin flat member by straight pressure. The clip will not only be bent inwardly, but will also be bent out of its original plane by buckling 15 over. The engagement of the inner end of the bore with the end of the clip causes the clip to buckle, since the clip is relatively thin in cross section, and relatively broad in elevation. Note in Fig. 3 that the effective thickness of the clip is 20 greater when it is distorted upon reaching the lower end of the bore than the thickness of the grooves which it has formed in the upper portion of the bore. Withdrawal of the clip is thus prevented, since the protruding edges are no 25 longer free to slide freely through the grooves formed in the walls of the bore during the introduction.

In all the preferred forms of the improved clip the leading extremities are adapted to bite into 30 the bamboo at the extremity of the hole, and when pressure is applied by the implement used, in the known manner, in the introduction of the clip and bristles, the clip is caused to tilt and/or bend in such manner that withdrawal of the 35 bristles and clip is effectively prevented.

My invention also consists in the improved method of anchoring bristles in the head of a bamboo tooth brush which method comprises mounting the bristles upon a clip having protruding side edges that groove the sides of the hole as 40 the bristles are introduced, forcing the clip carrying the bristles into the hole by means of a suitable implement and imparting a slight twisting or

turning movement to the implement when the clip is moved into its final position so that the protruding edges of the clip are prevented from alignment with the grooves formed in the walls of the hole with the result that the bristles and 5 clip are permanently anchored in place in the head of the brush.

Although the drawing and the above specification disclose the best modes in which I have contemplated embodying my invention, I desire to 10 be in no way limited to the exact details of such disclosure for in the further practical application of my invention changes in the dimensions and detail construction may be made as circumstances require or experience suggests without departing 15 from the spirit of the invention within the scope of the appended claims.

What I claim is:

1. A method of planting bunches of bristles in 20 bores formed in the head of a bamboo tooth brush, which comprises mounting the bunches of bristles upon retaining clips, forcing the clips into the bores while the side edges of the clips form diametrically opposed grooves in the walls of the 25 bores, and displacing and distorting the clips out 30 of the plane of the grooves at the extremities of the bores so that the said edges are moved from alignment with said grooves to prevent withdrawal of the side edges of the clips through said 35 grooves.

2. A method of planting bunches of bristles in 40 a bore formed in the head of a bamboo tooth brush, which comprises mounting a bunch of bristles upon a clip, forcing the clip into the bore in such manner that the edges of the clip form 45 grooves in the walls of the bore, and displacing the clip out of the plane of the grooves so that the edges are moved from alignment with the grooves, at the extremity of the bore, so as to prevent withdrawal of the clip through the said 50 grooves in the bore.

TORAZO NISHIO.
